POWER HAMMER

Campbell V. Adams, Chicago, Ill.

Original application February 4, 1931, Serial No. 513,269. Divided and this application July 29, 1932, Serial No. 625,755

11 Claims. (Cl. 61—76)

My invention relates broadly to power hammers and more particularly to the type of power hammers known as pile hammers, in which a ram is automatically operated by motive fluid supplied to the cylinder to impart motion to the ram. Although I shall refer throughout the present disclosure to this particular adaptation of my invention, it is to be understood that my invention is not to be limited to such use solely, but may be used broadly in the construction of power hammers. The present case is a division of my copending application, Serial No. 513,269, filed February 4, 1931.

In said copending application, the manner of distributing the motive fluid so as to operate the power hammer on the down stroke by motive fluid of substantially the same and constant pressure above the piston as below the piston is disclosed and claimed. The present application is directed to a unique form of housing construction for the cylinder and arrangement of parts.

An object of the invention is, therefore, to provide a new and improved design of housing for a power hammer having certain features of construction particularly applicable to a pile hammer.

A further object of the invention is to provide a housing for the cylinder of a pile hammer which is so arranged with respect to its associated parts as to protect the moving parts of the pile hammer, such as the ram and valve mechanism, the cylinder being also enclosed to insulate it from loss of heat and to provide a cool exterior surface, when employing a heated fluid, and also to make the hammer adaptable for subaqueous work.

A further object of the invention is to provide a housing for the cylinder of a pile hammer which may be formed into several parts and so connected together that either part may be removed to obtain access to the valve or valves, ram or cylinder, without removing or even disturbing the mounting of the cylinder within the housing.

A further object of the invention is to provide a simple cylinder housing design to accomplish the above mentioned results in a very efficient manner, the construction being simple, efficient and inexpensive, and requiring minimum attention and repair while the pile hammer is in service.

Other objects and advantages of my invention will be apparent from the following description taken in connection with the accompanying drawings which form a part hereof.

In the drawings,

Figure 1 is a side view partly in elevation and partly in section, with a portion of the housing

removed, of a power hammer embodying my invention;

Fig. 2 is a similar view, but showing a portion of the operating elements of the power hammer in section;

Fig. 3 is a horizontal sectional view taken on line 3—3 of Fig. 1;

Fig. 4 is a horizontal view looking down upon the power hammer, with the cylinder head removed, one-half of the view being in elevation 10 and the other half of the view being in section, to illustrate the manner of operating the valve actuating arms and of supporting the cylinder within the housing;

Fig. 5 is a view similar to Fig. 2, showing the 15 cylinder, ram, valve, actuating arms, cam and slide bar in elevation.

The power hammer disclosed herein is adapted to be operated by a motive fluid such as steam or compressed air, and is designed principally as a 20 power pile driver, but it is equally applicable for analogous purposes, as, for example, wherever a percussive blow is used, such as in rock drilling, riveting machines, concrete breaking or tamping and the like.

The power hammer comprises a suitable housing 1 provided with opposed guideways 2 in which guides of the usual supporting frame (not shown) are arranged to allow vertical movement of the hammer. Sheaves 3 may be arranged upon a 30 cylinder head 4 to receive cables or like flexible members controlling the vertical movement of the hammer within the frame.

Cylinder block 5 is attached to cylinder head 4. A piston 6 having a ram 7 attached at its lower 35 end is adapted to operate in cylinder 5, it being understood, however, that actual mechanical connection between the piston and the ram is not essential. The lower end of cylinder 5 is reduced in diameter at 8 to provide an auxiliary chamber 40 receiving an auxiliary piston 10 which forms a seal at the lower end of cylinder 5. The usual piston rings 11 may be employed to assure a tight seal.

Motive fluid for operating the power hammer 45 may be supplied by means of an inlet pipe connection 12, shown in Fig. 4, which communicates with a horizontal passage 13. Passage 13 communicates in turn with an annular chamber 14 disposed in cylinder 5 below piston 6 and directly 50 communicating with the cylinder below the piston at 15. Enlargement 16 formed on cylinder 5 provides a valve chamber 17 opening into chamber 14 at one side. Although I have shown a specific form of valve 18 arranged for actuation 55

in valve chamber 17, it will be specifically understood that the fluid distribution may be accomplished by a valve of any type and location. A rock pin 19, suitably mounted in fluid-tight relation in end heads 25 of enlargement 16, carries an admission trip arm 20 and an exhaust trip arm 21, formed on an enlarged boss 22, mounted exteriorly of enlargement 16, and also carries valve 18 in valve chamber 17. Valve 18 controls the admission and exhaust of motive fluid of two passages. One of these passages, passage 23, is vertically arranged and formed in the wall of cylinder 5 to provide controlled communication between valve chamber 17 and the cylinder above piston 6. The other passage 24 acts as an exhaust for the motive fluid thus supplied to the cylinder above the piston.

Timed movement of valve 18, by means of a slide bar 26 operating trip arms 20 and 21, controls the distribution of the motive fluid to the upper cylinder only, so that during the entire cyclic movement of piston 6 fluid will be supplied at full pressure below the piston, and will be supplied at the same or full pressure above the piston during the cushioning period of up stroke and accelerating period of the down stroke. As piston 6 reaches substantially the end of the down stroke, the motive fluid in the cylinder above the piston is exhausted to atmosphere, or otherwise, through passages 23 and 24. Fluid will again be admitted to the cylinder above the piston appreciably before the end of the up stroke. The purpose of admitting it at this period in the operation is to allow it to act as a cushion for the ascending piston, the motive fluid thereafter remaining in the chamber above the piston during the down stroke. Accordingly, the power hammer disclosed herein is adapted to have motive fluid of substantially the same and constant pressure acting on both sides of the piston during the down stroke. I find, therefore, that ram 7 may be made exceedingly heavy in proportion to dead weight for a selected driving energy and velocity of impact, it being understood that dead weight comprises all parts of the hammer serving to resist the net upward reaction of the fluid against the cylinder head 4. Not only may the ram be made exceptionally heavy in proportion to dead weight, which is one of the advantages of a single-acting hammer, but a more rapid succession of blows may be obtained, which is one of the advantages of a hammer of the double-acting type.

The power hammer herein described may be constructed with its moving parts, such as ram 7 and valve operating mechanism 20, 21 and 26, exposed for convenience, but on the other hand, they may be totally enclosed as shown for protection against damage or to permit the use of the device for sub-aqueous work, and to insulate the cylinder when using a heated fluid, thereby presenting a cool exterior surface to the touch and in addition reducing condensation in the cylinder by keeping the cylinder walls warm.

In order to provide relatively quick access to these operating parts, housing 1 has been preferably constructed of two parts, 30 and 31, arranged with opposed flanges 32 and 33 on opposite sides, adapted to be clamped together by suitable means, such as bolts 34. Reinforcing bosses 35 are integrally formed and spaced apart to provide increased reinforced bearing surfaces for said bolts 34.

Repair work on devices of this type may be greatly facilitated by allowing the cylinder, piston

and ram to remain mounted in housing 1 when possible. To accomplish this end, I provide diametrically opposed flanges 36 on cylinder 5, which flanges 36 are adapted to be bolted to the opposed flanges 32 of housing part 30 by means of cap screws 37, as shown in Fig. 4. Flanges 36 are adapted to fit snugly between flanges 32 and 33 as the result of laterally extending shoulders 38 formed on opposite sides of flanges 36, these shoulders providing a seat against which the flanges 32 and 33 may snugly fit. A connecting web 39 carries flanges 36 on cylinder 5. However, at the reduced lower end 8 of the cylinder, this web is reinforced by horizontal enlargements 40. Cap screws 37 do not pass through flanges 33. These cap screws 37 can only be removed after housing cover 31 has been removed.

If it is desirable to obtain access to the cylinder, ram or valve parts for the purposes of repair or the like, cap screws 37 need not be removed upon removal of housing cover 31. It will be noted in Figs. 3 and 4 that directly below flanges 36 a ram guide 42 is provided to guide ram 7 in its up and down movements. A guide-way 43 is formed on opposite sides of ram 7, as shown in Fig. 3, to receive guides 42. Guides 42 are provided with outwardly extending flanges 44, which are adapted to be clamped between flanges 32 and 33 of housing parts 30 and 31. Cap screws 45 function to secure guides 42 in position. Housing cover 31 may be also removed without removing cap screws 45 or disturbing the mounting of ram 7 within the housing.

Slide bar 26 is mounted upon ram 7. A portion of the ram at its upper end is cut away at 47, as indicated in Figs. 1, 3 and 10, and pocket 48 is provided to receive a head 49 carried by slide bar 26. Head 49 is clamped in position in pocket 48 by means of cover plates 51 removably secured in position by means of bolts 52. The slide bar 26 will thus move with ram 7 in its up and down strokes, in order that its cams 26' will operate the trip arms 20 and 21.

Although piston rod 53 may be of the same diameter as the auxiliary packing piston 10, I have shown it of smaller diameter and extending downwardly to connect with ram 7 by means of a split bushing 54. A spherical head 55 is formed on the lower end of piston rod 53 so that the upper face 56 of this head may bear against the lower end of split bushing 54, as shown in Fig. 2. The upper end of this bushing 54 may be suitably bolted at 57 to ram 7.

Any suitable form of construction at the lower end of the housing may be provided to accommodate the pile. There has been shown, however, a dolly plate 60 carried by a retainer 61 suitably attached to the lower end of housing 1 by means of the same bolts 70 as secure interposed seat 62. An impact plate 63 is disposed between the seat and the top of dolly plate 60.

Cylinder head 4 may be secured to the top of cylinder 5 in any suitable way. It will be noted in Fig. 4 that inwardly extending flanges 65 are formed at the upper end of housing parts 30 and 31, but these flanges are so formed as to provide spaces 66 through which inlet pipe 12 and exhaust pipe 67 are carried.

It will be understood that various details of construction of the housing may be changed without departing from the scope of the invention.

It is not essential that the motive fluid be supplied to the cylinder above the piston from the same source supplying the cylinder below the

piston. An exceedingly simple design may be obtained where the source of supply is the same, but the same advantageous results flowing from this form of fluid distribution may be had if separate sources are provided. It has been found that the inherent characteristics of the device disclosed resulting from this form of fluid distribution permit a wider latitude in the design of a power hammer to meet specified conditions.

10 For instance, by altering the stroke, the dead weight may be reduced or increased and the fluid pressure, weight of ram, striking energy and velocity of impact may be kept constant. The number of blows struck per minute may also be kept practically constant if desired, as the stroke is varied, by properly proportioning the design of the cylinder. Not only may the above advantages as well as many others be obtained, but greater economy in fluid consumption per unit of energy delivered by the blow is possible, due primarily to avoidance of exhausting fluid from large clearance space beneath piston 6, and to the lessened initial condensation occurring in the cylinder, as the hot fluid entering the upper end 25 of the cylinder on down stroke comes only in contact with surfaces previously heated by fluid underneath the piston.

Without further elaboration, the foregoing will so fully explain the gist of my invention, that others may, by applying current knowledge, readily adopt the same for use under varying conditions of service, without eliminating certain features, which may properly be said to constitute the essential items of novelty involved, which 30 items are intended to be defined and secured to me by the following claims.

I claim:

1. In a power hammer, the combination with a multi-part housing, a cylinder, a piston therefor and a ram connected to said piston, all of which are disposed within said housing, diametrically-opposed outwardly-extending flanges on said cylinder adapted to be clamped between adjoining edges of said housing parts for supporting said cylinder within said housing, and means for securing said cylinder in clamping relation between adjoining edges of said housing parts, said securing means fastening said cylinder and one of said housing parts individually together whereby the other housing part may be removed to provide access to the interior of said housing without detaching said cylinder.

2. In a power hammer, the combination with a multi-part housing, a cylinder, a piston therefor and a ram connected to said piston, all of which are disposed within said housing, radially extending flanges on said cylinder, means for fastening said flanges to the outer edges of at least one of said housing parts to support said cylinder within said housing, and means for securing the other housing part to the edges of the first housing part whereby said cylinder and said first housing part are individually secured together so that removal of the second housing part may be obtained without removing said cylinder.

3. In a power hammer, the combination with a multi-part housing, a cylinder, a piston therefor and a ram connected to said piston, means for mounting said cylinder within said housing comprising radially extending flanges disposed longitudinally along said cylinder, opposed longitudinal flanges on the parts of said housing, and means for securing said cylinder flanges between said flanges on said housing parts.

4. In a power hammer, the combination with a multi-part housing, a cylinder, a piston therefor and a ram connected to said piston, all of which are disposed within said housing, cooperating flanges on said housing parts and said cylinder to secure said cylinder within said housing, and means for fastening said flanges together whereby said cylinder and one of said housing parts are individually secured together so that the other housing part may be removed without removing said cylinder.

5. In a power hammer, the combination with a multi-part housing having a cylinder, a piston therefor and a ram connected to said piston disposed therein, means for fastening said cylinder to said housing comprising cooperating flanges on said cylinder and said housing, the flanges of said cylinder being arranged for clamping between the flanges of said housing, and fastening elements for securing said flanges together whereby said cylinder and one of said housing parts are individually secured together so that the other housing part may be removed without removing said cylinder.

6. In a power hammer, the combination with a multi-part housing having a cylinder, a piston therefor and a ram connected to said piston disposed therein, means for fastening said cylinder to said housing so that at least one of said housing parts may be removed without removing said cylinder comprising cooperating flanges on said cylinder and said housing, the flanges on said cylinder being arranged for clamping between the flanges of said housing, and a plurality of fastening elements, certain of which secure the flanges of said cylinder to the flanges of one of said housing parts while the others of which secure the flanges of the remaining of said housing parts to the flanges of said cylinder and said first housing part.

7. In a power hammer, the combination with a housing having a cylinder, a piston therefor and a ram connected to said piston, means for securing said cylinder within said housing including cooperating flanges on said housing and said cylinder, the flanges on said cylinder being carried between the flanges on said housing, and a guide for said ram disposed between the flanges on said housing below the flanges of said cylinder.

8. In a power hammer, the combination with a housing having a cylinder, flanges on said cylinder, a piston and a ram connected to said piston, guiding elements for said ram, and means for securing said cylinder and said guiding elements within said housing comprising means on said housing engaging said flanges on said cylinder and said guiding elements, and fastening elements therefor.

9. In a power hammer, the combination with a multi-part housing having a cylinder, a piston therefor and a ram connected to said piston, means for securing said cylinder within said housing including cooperating flanges on said housing and said cylinder, the flanges on said cylinder being carried between the flanges on said housing, a guide for said ram disposed between the flanges on said housing below the flanges of said cylinder, and means for securing the flanges on said cylinder and said ram guide to said housing in a manner providing for the removal of at least one of the parts of said housing without requiring the removal of said cylinder or said ram.

10. In a power hammer, the combination with a multi-part housing, a cylinder, a piston there-

for and a ram connected to the piston, all of which are disposed within said housing, means on said cylinder adapted to be secured to said housing parts substantially at the adjoining edges 5 of said housing parts for mounting said cylinder in a vertically suspended position within said housing, and means for securing said housing parts together with said cylinder mounting means in position, said securing means fastening said 10 cylinder and one of said housing parts individually together whereby the other housing part may be removed without removing said cylinder.

11. In a power hammer, the combination with a multi-part housing, a cylinder, a piston there-

for, and a ram connected to the piston, all of which are disposed within said housing, radially extending flanges disposed longitudinally along said cylinder adapted to be clamped between adjoining longitudinal edges of said housing parts 5 for mounting said cylinder in a vertically suspended position within said housing, means for securing said radially extending flanges to the edges of one of said housing parts, and means for securing the edges of the other housing part to 10 the edges of the first housing part with said radially extending flanges therebetween. 5

CAMPBELL V. ADAMS.
